UNITED STATES PATENT OFFICE.

STEPHEN J. MEEKER, OF NEWARK, NEW JERSEY.

DESIGN FOR A HOSE-REEL BRACKET.

SPECIFICATION forming part of Design No. 20,530, dated February 24, 1891.

Application filed July 10, 1890. Serial No. 358,354. Term of patent 14 years.

To all whom it may concern:

Be it known that I, STEPHEN J. MEEKER, a citizen of the United States, residing at the city of Newark, county of Essex, and State of New Jersey, have invented and produced a new and original Design for Hose-Reel Brackets, of which the following is a specification, reference being had to the accompanying drawings, forming part thereof.

My invention relates to the design configuration of the bracket for supporting a hose-reel and is illustrated in the accompanying drawings, in which—

Figure I represents a side view, and Fig. II represents a plan view.

Similar letters indicate similar parts.

The letter A indicates the bracket, which is formed of a yoke, each of the side portions

B of which is tapered toward its end or extremity and rounded at that point, each being substantially a counterpart of the other. In these side portions B of the yoke are openings C, Fig. I, conforming in outline with the top and bottom edges thereof, and above and below this opening is a rib e, extending parallel to said edges. By these features I obtain a bracket of light and graceful appearance and of a character to be readily distinguished from other articles of a similar nature.

What I claim is—

A design for a hose-reel bracket, substantially as shown and described

STEPHEN J. MEEKER.

In presence of—

LOUIS W. FROST,
JOSEPH A. COLLINS.
